UNITED STATES PATENT OFFICE.

WILLIAM M. STEINLE, OF ALLEGHENY CITY, PENNSYLVANIA, ASSIGNOR TO HIMSELF AND JOHN K. COLLINS & BROTHER AND CYRUS A. DODD, ALL OF SAME PLACE.

CIGAR-MACHINE.

SPECIFICATION forming part of Letters Patent No. 244,333, dated July 12, 1881.

Application filed April 9 1881. (Model.)

To all whom it may concern:

Be it known that I, WILLIAM M. STEINLE, of Allegheny City, in the county of Allegheny and State of Pennsylvania, have invented a new and useful Improvement in Machines for Making Cigars; and I do hereby declare the following to be a full, clear, and exact description thereof, reference being had to the accompanying drawings, forming part of this specification, in which—

Figure 1 is a side elevation of my improved machine. Fig. 2 is an elevation of the opposite side. Fig. 3 is a vertical longitudinal section. Fig. 4 is a view of the geared folding-roll. Fig. 5 shows the receiving-table and delivery-slide 41. Fig. 6 shows the pinion, pawl, and ratchet of the traction-roll 11. Fig. 7 shows the pinion, pawl, and ratchet of the feed-roll 9. Fig. 8 shows the shaft 25 and cams 23 and 24. Fig. 9 illustrates the operation of the cams 23 and 24 upon the presser-plate 21. Fig. 10 shows the belt-stretching roll 39. Fig. 11 shows the cutter and cutter-frame. Fig. 12 shows how the folding-rolls are opened by the cutter-frame and the folding-belt creased. Fig. 13 shows how the filler is pushed in between the folding-rolls. Fig. 14 shows the construction of the cone-pulley 126. Fig. 15 shows the construction of the devices for driving the bobbin. Fig. 16 shows the operation of the creaser 50 and blade 143 in enveloping the bunches. Fig. 17 shows how the feed-web is used to envelop the finished bunches. Fig. 18 shows the manner of adjusting the guides 42 and 43 to suit different sizes of cigars. Fig. 19 is a side view of the roll 28. Fig. 20 is a perspective view of the flattening-brush 16 and curved strippers 15. Fig. 21 is a sectional view of one end of the bobbin, and Fig. 22 shows the attachment of the devices for operating the stretching-roll 38.

Like letters of reference indicate like parts in each.

In explanation of certain terms used by me in this specification, I will say that "filler" means the tobacco which composes the body of the cigar, "binder" the inside wrapper, "bunch" the filler rolled up in the binder, and "wrapper" the outside cover or layer.

My improvement consists of a machine for 50 making the bunches of cigars, which takes the tobacco in the shape of a continuous feed or web, flattens and smooths the said web, cuts it into sections, with thick and thin ends laid alternately in the reverse directions, and 55 incloses each of such sections in a binder, rolls the same around it, and delivers the bunch in a rolled, compact, and complete condition, ready for the application of the wrapper.

For greater clearness I will first describe the 60 operation of the machine, and then the devices by which the movements are given to the various parts.

The working parts of the machine are all mounted upon a suitable frame, 1. At one 65 end is a box or frame, 2, provided with vertical guides or ways 3 on opposite sides, which guides are designed to receive the journals of a spool or bobbin, 4, upon which is a web of cloth, 7. Wound in the folds of the web 7 is 70 a layer of tobacco, such as is used in making the fillers of cigars. The tobacco is in a sufficiently damp condition to be easily formed into fillers and retain the shape which is given to it, being of a fibrous nature. Mounted upon 75 rollers 5, under the spool 4, is a belt, 6, which is designed to relieve the web 7, in its forward movement, from friction, the belt 6 turning with the web 7.

Beyond the inner end of the web 7, and extending in a lower plane, is a belt, 8, mounted on rolls 9 and 10, to which a positive motion is given by suitable gearing. The web 7, after passing over the roll 5, turns back over the roll 9, passes under the roll 11, and is wound upon 85 the roll 12 as it is drawn off of the spool 4, the traction being given by the roll 11, to which power is applied for that purpose. The roll 12 is mounted on a swinging frame, 52, journaled at 53, and provided with a short arm, 54, against 90 which a spiral spring, 55, bears, for the purpose of pressing the roll 12 up against roll 11, by a yielding pressure, which will permit it to take the increasing bulk of the web 7 as it is wound upon it. The tobacco is separated from the 95 web 7 as the latter passes back over the roll 9, and falls upon the belt 8, by which it is carried forward into the machine, under the curved

5 fingers or strippers 15, which, in connection with a rotary brush, 16, working between them, flattens and smooths it out into a suitable layer and compresses it on the belt 8. After passing the curved fingers 15 it comes in contact with the belt 13, mounted on rollers 14, which belt, pressing upon the upper surface and operating in connection with the belt 8, feeds it forward into the guides 17.

10 Beyond the guides 17 is a vertically-moving cutter, 57, which is mounted on a vertically-reciprocating frame 58, said frame being operated by means of a rock-shaft, 59, and arm 60, and moving in guides 61. Beyond the cutter 15 57 is a vertically-moving plunger and folding-blade, 18, which is reciprocated by a rock-shaft, 19, the arm 20 of which extends through a suitable slot in the stem of the plunger. Beyond the plunger 18, on the side opposite to 20 that occupied by the guides 17, is a pivoted gage and presser-plate, 21, sustained by pivoted hangers 22. The inner sides of the guide 17 and the presser-plate 21 constitute the sides of the cutter cavity.

25 As a cigar is thicker at one end and tapers to the other, it is necessary to cut the filler-sections of corresponding form from the sheet of tobacco that is fed through the guides 17. To accomplish this the presser-plate 21 is inclined laterally in opposite directions alternately of each stroke. This is done by means of the cams 23 and 24, mounted upon the shaft 25, and placed back of the presser-plate 21. The shaft 25 is turned after each stroke of the cutter 30 57, so that one or the other of the cams, 23 or 24, which bear against the opposite ends of the presser-plate shall be thrown forward alternately against the plate and the other withdrawn, thus causing one end of the presser-plate to be advanced in the cavity nearer to 35 the opposite side. At the further operation of the machine the first cam retires and the other cam advances, causing the cutter-cavity to be tapered in the opposite direction. While the 40 knife 57 is elevated the tobacco is fed through the guides 17 until it comes in contact with the presser-plate 21, and being soft, it adapts itself to the cavity into which it is fed, and thus 45 enables me to cut fillers which taper alternately in opposite directions.

50 Back of the shaft 25 is a feed-table 26, for feeding the binders into the machine. At the inner end of table 26 and extending diagonally downward, is a feed-guide, 27, which leads to 55 a pair of folding-rolls, 28 and 29, directly under the plunger. The purpose of the feed-guide is to feed the binder directly over the pass of the folding-rolls, so as to receive the section of the tobacco as it is carried down by the plunger 18. One of the folding-rolls, 28, is mounted in the upper end of an oscillating frame, 30, and the other, 29, in a pair of levers, 31, journaled in the frame 30 at 33, and each provided with a heel or tail, 32. The frame 30 oscillates 60 upon the counter-shaft 35, and when at the end of its oscillation, or nearly so, the heels 32 of the levers 31 come in contact with the stops 65

34, which trip them and throw the roll 29 away from roll 28 to discharge the bunch.

Extending from a roll, 38, around roll 39, 70 and down between the folding-rolls 28 and 29, forming a loop, 150, and thence forward to roll 40, upon which it is wound, is a loose belt, 37. The roll 39 has reverse tapers on its opposite sides, which tapers correspond to those of cigars placed in the same position. These reverse tapers are alternately turned up under the belt 37, so that when the latter is stretched over the roll during the forward movement of the frame 30 it will assume a shape corresponding to the shape of the filler in the folding-rolls. Then at the next motion of the machine the roll 39 will be turned so as to bring the reverse taper forward. This movement of the roll 39 corresponds to that of the presser-plate 21. In the oscillation of the frame 30 the folding-rolls 28 and 29 are carried forward upon curved guides 36, above which curved guides, on each side, is a parallel curved rack, 56, in which gear the teeth or pinions on the 80 ends of the roll 29, so as to communicate to said roll a positive rotation and draw the belt 37 positively over to it. The binder is fed down upon the folding-rolls 28 and 29 directly under the plunger 18, so that when a section 85 of tobacco is cut off it is forced down by the plunger upon the said binder, and the binder and tobacco are forced between the rolls 28 and 29 into the loop or slack of the belt 37. This causes the binder to fold up around the 90 tobacco, and then the frame 30 is caused to move forward on the curved ways 36. The operation of the racks 56 upon the pinions of the roll 29 causes the roll 29 to have a positive rotation and to be forced inward toward 95 the roll 28, so as to tightly inclose the filler, which is in the loop 150, and not permit it to escape from between the rolls 28 and 29. The movement of the frame 30 causes the belt 37 to be drawn around the roll 29, around the 100 filler, and over the roll 28, and this causes the filler to be rotated in the loop of the belt 37 between the folding-rolls, the binder to be folded around it, and the bunch thus made to be compressed and formed. As the belt 37 is 105 sufficiently loose it will draw freely between the rolls 28 and 29 and around the filler when the frame 30 moves forward in its oscillation. When the frame 30 reaches the roll 40 the bunch will have been relieved from the pressure of the belt by the heels 32 of the levers 31 coming in contact with the stops 34 and opening the rolls 28 and 29, and the loop of the belt 37 being taken up by the movement of the rolls past the roll 40, to which its end is 110 fastened, the bunch will be discharged from the belt onto the upper end of the table or guide 43.

At the lower end of the cross-guides 36, mounted in suitable ways, is a reciprocating 115 slide, 41, which, when the bunch is discharged on the upper end of the table 43, pushes it down the said table, and so aids in delivering the bunch from the machine.

Below the slide 41 there is a web, 44, which is drawn from the roll 45, passes up around the roll 46; thence down under the table 41, and over and along the curved guide 43 to a roller, 47, at the front side of the machine. A curved guide, 42, extends from beneath the roller 40 down to the bobbin 47, a short distance above the guide 43, and nearly parallel thereto. When the bunch is discharged from the belt 37 and falls on the table 43 it rests upon the web 44, and travels on it down between the guides 42 and 43, and is wound up with it on the bobbin 47.

Under the bobbin 47 is a belt, 48, passing around the rolls 49, which is designed to sustain the web and bunches as they pass to and are wound upon the bobbin. When a sufficient coil of bunch has been formed the bobbin is taken off and the bunches removed for use. The bunches are permitted to remain on the bobbin, within the spiral folds of the web, until sufficiently dry for use, or they may be preserved damp in this position. This method of preserving them is of great utility, as it keeps them in shape, preserves their flavor, and is an economical way of putting them up. They may be sold to the dealers in this shape, who can then apply any quality and color of wrapper they desire. Common cigars are wound on the bobbin by the simple spiral folds of the cloth, (see Fig. 5;) but fine cigars are enveloped thereby, as shown in Figs. 16 and 17.

I will now proceed to describe the devices for communicating power to the various parts of the machine.

The machine is operated by a foot-treadle, 62, mounted on a shaft, 63, and provided with a crank, 64, which is connected to the main shaft 65, at one end, by means of a link, 66, and crank 67. On the other end of the main shaft there is a fly-wheel, 68, and at one side is a counter-shaft, 35, to which power is communicated by means of the pinion 69 on the main shaft, meshing into a large gear-wheel, 70, on the counter-shaft. There is an eccentric, 71, on the counter-shaft 35, upon which is a yoke, 72, connected by a rod, 73, to the lever 74, which is journaled on the shaft 75. The lower end of the lever 74 is connected to the lower cross-head, 77, of the pivoted frame 30 by means of a link or rod, 76. The purpose of this connection is to communicate the oscillating movement to the frame 30, by which the rollers 28 and 29 are carried down the curved guides 36 in forming the bunches and discharging the same.

I have already explained the operation of opening the folding-rolls by means of the stops 34. To keep the folding-rolls closed until opened by said stops I have placed a spring, 78, on each arm of the frame 30, the other ends of which are connected to the levers 31 in such a manner as to keep the folding-roll 29 in close proximity to the folding-roll 28, and to retract the levers 31 as soon as the swinging frame 30 moves back from contact with the stops 34. The reciprocating movement is

given to the slide 41 by means of links 79, pivotally connected to the ends of said slide and to the oscillating frame 30, and the operation thus given to the slide is such that when the frame 30 is at the forward end of its oscillation and discharging the bunch from the folding-rolls the slide 41 is drawn back, so as to permit the said bunch to fall down upon the table 43 in front of it, and then when the frame 30 is retracted the slide 41 will be drawn forward and push the bunch down in front of it along the table 43, as shown in Fig. 3.

Pivotedly attached to the frame 30, at one side of the machine, and extending in an opposite direction from the links 79, which operate the slide 41, is a rod, 80, the other end of which is pivotally connected with the lower end of the lever 81, which, in turn, is pivoted to the frame of the machine at 83, and provided at its upper end with a segmental gear, 82. The gear 82 meshes into the pinion 84 upon the shaft 85 of the roll 11. On the shaft 85, and inside of the pinion 84, is a ratchet, 86. (See Fig. 6.) The pinion 84 is loose on the shaft 85, and is provided with a pawl, 87, which plays in the ratchet 86, being held down upon the ratchet by a spring, 88, attached to the inner face of the pinion.

The operation of this part of the machine is as follows: When the frame 30 makes its forward movement in rolling and delivering the bunch it causes the pinion 84 to be turned by means of the segmental gear 82, and as the pinion during the forward movement of the frame 30 will be held to the shaft 85 by means of the pawl 87 taking into the ratchet 86 it will cause the roll 11 to turn. The extent of the rotation of the roll 11 thus produced is limited to the forward movement of the frame 30, and is regulated by the adjustment of the rod 80 upon the pivoted lever 81, which adjustment is effected, preferably, by means of a sliding box, 89, provided with a set-screw, 90. By raising the box 89 on the lever 81 the movement is lengthened, and by dropping it it is shortened. The backward movement of the frame 30 causes the pinion 84 to be turned in the reverse direction, and by such movement the pawl 87 will slip over the ratchet and the roll 11 will remain stationary. As before described, the purpose of the roll 11 is to feed the tobacco onto the belt 8 and to wind the web 7 up on roll 12. This feed is made intermittent, because the operation of the machine is necessarily intermittent, owing to the folding and rolling operations which follow the feed. It is necessary to wind the web 7 on the roll 12 instead of on the traction-roll 11, as otherwise the latter would gradually grow larger and increase the speed and amount of feed, which would ruin the operation of the machine.

Power is communicated to the roller 9 to turn the belt 8 by means of a pinion, 91, on the end of roller 9, which pinion intermeshes with the pinion 84 on the roll 11. The pinion 91 is loosely mounted on its shaft, which is provided

with a ratchet, 92, a pawl, 93, and a spring, 94, similar to the corresponding devices on the roller 11. (See Fig. 7.) These devices impart a rotary motion to the roller 9 during the 5 reverse motion of the pinion 84, so that when the pinion 84 is not turning the roll 11 it is turning the roll 9 through the medium of the pinion 91. This causes an intermittent forward motion of the belt 8 immediately after the forward feed of the web 7, and alternately therewith.

Extending from the cross-head 77 of the pivoted frame 30, in the opposite direction from the link or rod 76, is a rod or link, 95, which 10 is pivotally connected to the lower end of the ratchet-lever 96. The lever 96 is pivoted to the frame of the machine, and operates, in connection with the ratchet 97 on the end of one of the rolls 49, to communicate an intermittent motion to the belt 48, and thereby aid in winding up the web 44, with the bunches, upon the bobbin 47. The bobbin 47 is mounted on the end of the frame 98, which is pivoted on the shaft 99. It is held down upon the belt 48 by the pressure of the spring 55, which extends between the shaft 99 and the short arm of the lever 52, and exerts a torsional strain against the cross-piece 100 of the frame 98. The purpose of this construction is to accommodate 30 the gradually-increasing size of the bobbin as the web 44 and bunches are wound upon it.

On the counter-shaft 35 there is a pinion, 101, which meshes into the gear-wheel 102, 35 mounted on a journal extending out from the frame of the machine. A link, 103, is connected by a suitable wrist-pin to the gear-wheel 102, and to the forward end of the lever 104, which is pivoted to the frame of the machine 40 at 105.

Extending up from the lever 104 is a link, 106, the upper end of which is pivotally connected to one arm of the bell-crank 107. The other arm of said bell-crank is connected by a link, 45 108, to the crank 109, which is mounted upon the end of and operates the shaft 25. This shaft, as before explained, carries the cams 23 and 24, (see Fig. 8,) which, operating alternately against the opposite ends of the press- 50 er-plate 21, change the shape of the cutter-cavity, as before described, to suit the alternately-reversed position of the thick and thin ends of the filler. (See Fig. 9.) The same device effects the reversal of the roll 39, so as to 55 bring its reversed tapers (see Fig. 10) to correspond to the shape of the cigar being formed. The said roller 39 is provided with a pinion, 110, into which meshes a segmental gear, 111, on the lower arm of the bell-crank 107. The 60 movement causes the roll 39 to make a half-revolution at each stroke of the machine, and brings the thick side of the roll uppermost alternately on opposite ends, so as to cause the belt 37, which is stretched over it, to assume 65 the shape of the filler, which is forced down between the folding-rolls by the plunger 18. The other two sides of the roll 39 are made

straight or parallel, so that when it is desired to make a straight cigar the pinion is slackened and the roll turned in it so as to bring the straight sides of the roll into contact with the belt 37. Then when the plunger descends between the folding-rolls and tightens the belt it will tighten it over a plain surface, and thereby produce a parallel fold between the 75 folding-rolls.

Mounted on the counter-shaft 35 is a cam, 112, on which bears the front end of the lever 113, which lever is pivoted at 114, and has a rod, 115, connected therewith and extending up to and connected with the crank 116 on the end of the shaft 59. These devices operate the cutter-frame 58, the operation of which has already been described. The lever 113 is held by the cam 112 by its own weight. There is a second cam, 117, arranged alongside of the cam 112, on the counter-shaft 35, which is designed to operate the plunger 18 by means of a lever, 118, pivoted at 114, and connected to the crank 120, on the end of the rock-shaft 19, by means of a rod, 119. The operative surface of the cam 112 is longer than that of the cam 117, so that the corner-posts 121 of the cutter-frame 58 (see Fig. 11) shall descend first and open the folding-rolls, and hold them open during the operation of the plunger. (See Fig. 12.) This cam 117 is so arranged that it shall cause the operation of the plunger 18 after the descent of the cutter-frame 58, and as the stroke of the plunger is much shorter than that of the cutter-frame, owing to the difference in the cams 112 and 117, the stroke of the plunger shall be completed before the cutter-frame is withdrawn and the folding-rolls permitted to close. In this way the folding-rolls are held open and the plunger permitted to force the filler and binder in between the folding-rolls and stretch the belt, Fig. 13, without having to do the work of opening the said rolls, thereby preventing the crushing of the 110 tobacco and preserving the shape of the filler. 105

Extending inward from each of the side pieces, 121, of the cutter-frame is a finger, 122, Fig. 11, which is held on the edge of the belt or web 37, when the cutter-frame descends between the folding-rolls, and carries the belt down in between the folding-rolls, forming the loop 150, into which the binder and filler are tucked. These fingers, operating on the edge of the belt, do not interfere with the forcing 120 of the filler between them, and can be retracted without touching the filler.

The brush 16 is operated by means of a belt, 123, extending between and around the pulley 124 on the power-shaft 65, and the pulley 125 on the end of the brush-shaft.

At the delivery end of the machine is a cone, 126, mounted on the end of the shaft 99, to which is attached a cord, 127, which passes up over a pulley, 128, and is provided with a 130 weight, 129. On the shaft 99, at the inner end of the cone 126, is a loose pulley, 130, from which extends a belt, 131, to and around the pulley 132 on the end of the bobbin-shaft 47.

The loose pulley 130 is connected to the shaft 99 by means of the pawl 133 taking into a ratchet, 134, on the cone 126, so that when the shaft 99 is turned by means of the weight 129 5 the pulley 130 will be turned and will operate the belt 131, and thereby turn the bobbin-shaft 47 in winding up the bunches as they are pushed through by means of the slide 41. The power of the weight is sufficient to take up 10 the slack produced by the operation of the slide 41, but is not sufficient to draw the web 44 through without the aid of the slide 41. The shaft 99 is provided with a crank, 135, for the purpose of winding up the cord 127 and 15 raising the weight 129. When the shaft 99 is turned in winding up the weight the pawl 133 slips over the ratchet 134, and the pulley 130 remains stationary.

To insure against the turning of the pulley 130 during the winding up of the weight I 20 have provided a pawl and ratchet, 136 and 137, on the end of the bobbin-shaft. The pawl 136 slips over the ratchet 137 during the forward movement of the belt 131; but in case the belt 25 131 is reversed by the movement of the shaft 99 in winding up the weight the pawl 136 falls into the ratchet 137 and prevents the back movement of the bobbin-shaft, and so will 30 guard against the spoiling or unwinding of the bunches on the bobbin. The movement 35 of the weight 129 is sufficient to wind up one bobbin, each of which holds from seven hundred to one thousand bunches. The purpose of giving the cone shape to the winding-drum 40 126 is to increase the power of the weight, as the diameter of the bobbin increases with the winding up of the web upon it. The cord is fastened to the small end of the cone, so that at each turn the diameter of the coil is enlarged and the power of the weight increased.

The rollers 10 and 14 are geared together 45 by suitable pinions, 138, for the purpose of communicating the power of the belt 8 to the belt 13, and obtaining an equal forward feed on both sides of the filler.

The effect of the rotation of the filler in the belt 37 during the forward movement of the oscillating frame 30 is to compact the filler and reduce its diameter, thereby producing 50 slack in the belt. In order to take up this slack I communicate a partial rotation to the roll 38, Figs. 2 and 22, to which the rear end of the belt 37 is attached, by means of the following devices: A crank, 139, is fastened to 55 one end of the roll 38, which crank is connected by a link, 140, to one side of the frame 30, so that when the frame 30 makes its forward motion it turns the roll 38 sufficiently to take up the slack of the belt 37, produced by the 60 reduction of the diameter of the filler therein. The slack thus produced is necessarily slight, and hence the rotation given to the roll 38 will usually not exceed a quarter of a revolution. The amount of this rotation may be regulated by changing the point of attachment 65 of the link 140 to the frame 30. By attaching

it higher the rotation is increased, and by attaching it lower it is diminished.

Pivoted at the end of the machine to the shaft 51 is a creaser, 50, which, when the slide 41 is pushed back, falls over the edge of the slide and creases the cloth for the reception of the bunch. Then when the bunch is discharged from between the folding-rolls it falls against the face of the creaser and is guided thereby 75 down into the crease in the web 44. The creaser is used in this way when it is designed to envelop each bunch with the web 44. To do this (see Fig. 16) the slide 41 is provided 80 with a blade, 143, secured upon its upper face and projecting beyond its edge, so that when the slide advances to force the bunch down the inclined table 43 the blade 143 tucks the web over the top of the bunch, and in under the top of the guide 42, while the concave front 85 edge of the slide forces the bunch and enveloping web down along the table 43. The retraction of the slide 41 causes the withdrawal of the blade 143, and leaves the cloth enveloping the bunch. This operation is repeated 90 with every bunch as it is delivered upon the table 43. When the bunches are enveloped in this way it is necessary to use a second web, in order to keep the web from pulling off of them when wound around the bobbin, as otherwise 95 the web 44 would be drawn from around the bunches by the winding operation. I prevent this by making use of the filler-web, which, as before described, is wound around the roll 12. Instead of winding it up on the roll 12, I pass 100 it around the roll 12, then down around the outer roll, 49, along parallel with the belt 48, into and around the inner roll, 49, and then around the outside of the web 44 as the latter is rolled on the bobbin 47, Fig. 17. It is apparent that after the end of the web 7 has 105 been brought in this course and started on the bobbin 47 it will be drawn onto it and wound up with the web 44, and be interposed spirally between the coils on the web 44, with its 110 enclosed bunches upon the bobbin, and prevent the inclosing-web 44 from being drawn off of the bunches. By thus enveloping each bunch separately in the folds of one web the contact 115 of bunches is prevented, so that they dry more uniformly and regularly, and without becoming distorted, while by using a continuous web for both the bunch-folds, web 44, and the securing or spiral folds, web 7, I am enabled to 120 fill the bobbin 47 automatically from the machine.

The creaser 50 is used merely as a guide where it is not desired to envelop the bunches with the web 44. In such case the web 44 passes under the slide 41, (see Fig. 5,) and the 125 bunches are laid upon it side by side as they are delivered from the folding-rolls; but when it is desired to envelop the bunches with the web 44, as described, the said web must pass over the top of the slide 41, in order to be 130 creased and tucked around the bunches, as described.

The length of the belt 37 is adjusted to suit the size of the bunch to be made by means of the roll 40, which is provided with a ratchet, 144, held in position by the pawl 145.

5. The position of the curved guide 42 with relation to the curved guide 43 is regulated by means of adjusting-screws 146, working through the guide 43 into the guide 42, Fig. 18, so as to enlarge or diminish the distance 10 between them to suit the size of the cigar to be made.

The spring 141, attached to the lower cross-head, 77, and to the cross-head 75, is provided for the purpose of retracting the oscillating 15 frame 30 after the completion of its forward movement. The link 76 is slotted, as at 148, to permit this retraction of the frame 30 immediately upon the completion of its stroke, instead of waiting for the slow movement of 20 the eccentric 71. The reason for this speedy retraction of the frame 30 is to enable it to be charged by the time the eccentric comes around and is ready to carry it down again.

The bobbin 47 is recessed at its end, and is 25 mounted in its frame by means of pins or journals 142 projecting into the said recesses, Fig. 21. One of these journals is provided with a spiral spring, 149, bearing against the frame and forcing the pin inward. By drawing 30 the pin outward against the pressure of this spring the bobbin is released, and may be taken out of the frame.

The roll 45 is provided with a removable shaft, 151, so that it may be removed from the frame 35 by withdrawing the shaft when it is desired to replace the web 44.

The advantages of my improved machine are, that it will make more bunches in a day than several expert workmen, and will produce more compact, shapely, and uniform work; that it requires but little power to run it, and needs but one attendant to operate it, and that it is simple and easy to operate, and not liable to get out of order.

45 I am aware that a series of pockets or cells adapted for the reception of eggs and other articles has been formed by combining corrugated strips having their ends connected with interposed plain strips, and do not herein claim 50 such a device, as it could not be filled from a continuously-operating machine of the class herein described.

What I claim as my invention, and desire to secure by Letters Patent, is—

55 1. The method herein described of making cigar fillers or bunches, consisting in severing a series of alternately reversely-tapering sections from a continuous sheet, and subjecting such sections to a forming or shaping pressure 60 between forming-surfaces which change direction from time to time to conform to the taper of the succeeding sections, substantially as and for the purpose specified.

2. The method herein described of packing 65 cigar-bunches for drying, transportation, and trade, the same consisting in enveloping the

bunches separately within the folds of one continuous web, whereby contact between the bunches is prevented, and then coiling or winding the said web and its contents upon a bobbin by the aid of an additional web continuous spirally wound, which supports the first web and preserves its folds, substantially as specified. 70

3. As an article of trade, a package or bundle 75 of fillers or bunches, each filler or bunch separately enveloped in the folds of a continuous web, and the series secured about a suitable bobbin by the spiral folds of a second continuous enveloping-web, substantially as and for the purpose specified. 80

4. In a machine for forming cigar-fillers from a continuous sheet of filler material, the combination of a bobbin having a continuous web for supporting and delivering a continuous 85 sheet of filler, a carrier for receiving the sheet of filler from the web of the bobbin and delivering it to the cutter, and a cutter for severing filler-sections from the continuous sheet of filler material, substantially as specified. 90

5. In a machine for forming cigar-fillers from a continuous sheet of filler material, the combination of a bobbin for holding and delivering the sheet of filler material, said bobbin having sliding journals which permit it to preserve its contact with the driving apron or belt, a friction driving belt or apron, upon which the surface of the bobbin rests to obtain a uniform rate of feed, and a cutter for dividing the continuous sheet of filler material into 100 filler-sections of uniform size, substantially as specified. 95

6. In a cigar-machine, the combination of a bobbin or filler-roll provided with a web for supporting and feeding a continuous sheet of 105 filler material, a traction-roll for drawing off the bobbin-web at a uniform rate of speed, and a traveling carrier-belt for receiving and delivering the continuous sheet of filler material, substantially as and for the purpose specified. 110

7. In a cigar-machine, the combination of a bobbin or filler-roll provided with a web for supporting and feeding a continuous sheet of filler material, a traction-roll for drawing off 115 the bobbin-web at a uniform rate of speed, a receiving-roll for receiving the bobbin-web, said receiving-roll held against the traction-roll by an elastic yielding pressure to receive its motion from the traction-roll, and a carrier belt or apron to receive the continuous sheet of filler material and deliver it to the cutter, substantially as and for the purpose specified. 120

8. In combination, a filler feed-belt, a rotating, spreading, and compacting brush operating on the filler upon the surface of said belt, and a cutter for severing the compacted filler-sheet into sections, substantially as and for the purposes described. 125

9. In a cigar-making machine, the combination, with a filler feed-belt, of a rotating, spreading, and compacting brush operating through 130

- parallel fingers or strippers, substantially as and for the purposes described.
10. The combination of a pair of folding-rolls, a reciprocating frame having a knife which cuts off a section of filler, and corner-posts which open the folding-rolls, and a reciprocating plunger which forces the section down between the folding-rolls, substantially as and for the purpose described.
10. 11. A cutter-cavity having a movable side, in combination with devices bearing against it which alternately change the taper of the cavity at each stroke of the machine, substantially as and for the purpose described.
15. 12. The combination of an oscillating frame having a pair of folding-rolls on its outer end, said rolls adapted to open and close to permit the passage of a filler, a slack belt which extends over and forms a loop between the folding-rolls to receive a filler, and curved ways for the rolls to travel on, substantially as and for the purposes described.
20. 13. The combination of an oscillating frame having a pair of folding-rolls one of which has pinions on its ends, curved ways for the rolls to travel on, curved racks operating to turn the pinioned roll, and a slack belt passing over and forming a loop between the folding-rolls, substantially as and for the purposes described.
30. 14. An oscillating frame having a pair of parallel folding-rolls, one of which is journaled in the outer end of the frame and the other in a pair of levers pivoted thereon, in combination with tripping devices for opening the rolls at the end of the movement of the oscillating frame, and a slack belt adapted to form a loop between the folding-rolls, substantially as and for the purposes described.
35. 15. An oscillating frame having a pair of parallel folding-rolls, one of which is journaled in the outer end of the frame and the other in a pair of pivoted levers having tail-pieces and held closed by suitable springs, in combination with stops which engage the said tail-pieces and open the rolls at the end of the movement of the oscillating frame, and a slack belt adapted to form a loop between the rolls, substantially as and for the purpose described.
40. 16. In combination with the oscillating frame having folding-rolls and belt, a receiving-table, and a feed-slide which pushes the bunches forward after they are discharged from the folding-rolls, substantially as and for the purpose described.
50. 17. The combination of a creasing device, a reciprocating folding-blade guides, and an enveloping-web, which passes between said creasing device and folding-blade, substantially as and for the purpose described.
55. 18. The combination of the enveloping-web with adjustable guides, between which it and the bunches pass on their way to the bobbin, a
- web-creaser, and a reciprocating bladed slide, substantially as and for the purposes described.
19. In a cigar-making machine, the combination of a receiving-table or guide to receive the bunches from the forming devices, a receiving bobbin provided with a web which extends over the receiving-table for the purpose of enveloping the bunches, said receiving-bobbin mounted on a yielding or pivoted frame, and an independent belt or apron arranged below and adapted to support the receiving or bunch bobbin, substantially as and for the purpose specified.
20. The combination, with the shaft of the receiving-bobbin and its web 44, of a pulley operated by a weight, and suitable intermediate mechanism for transmitting the power from the pulley to the bobbin-shaft, substantially as and for the purpose specified.
21. The combination, with the shaft of the receiving-bobbin and its web 44, of a pulley operated by a cord and weight, a cone-shaped drum for continuously increasing the power of the weight upon the pulley, and suitable intermediate mechanism for transmitting the power from the pulley to the bobbin-shaft.
22. The combination of the bunch-enveloping web and the receiving-bobbin, with a reciprocating slide forcing the web down toward the bobbin, and a pulley and weight which exert a winding power on the bobbin, substantially as and for the purposes described.
23. The combination, with the rolling or folding belt, of the shaping-roll 39, having reverse tapers on opposite sides, with suitable mechanism to give it a half-turn at each operation of the machine, substantially as and for the purposes described.
24. The combination of the shaping-roll, the rolling-belt, the folding-rolls, and the stretching-roll to which the end of the belt is fastened, the said stretching-roll making a partial revolution to take up the slack of the belt as the filler is reduced in size by the rolling operation, together with suitable mechanism for actuating the several rolls, substantially as and for the purposes described.
25. The combination, with the folding-rolls, of a reciprocating cutter-frame operated by a long cam, in combination with the reciprocating plunger operated by a short cam, said cams mounted on the same shaft, so that the stroke of the plunger shall be made and completed during the stroke of the cutter, substantially as and for the purpose described.

In testimony whereof I have hereunto set my hand.

WILLIAM M. STEINLE.
